UNITED STATES PATENT OFFICE.

HARRY M. RYDER, OF WILKINSBURG, PENNSYLVANIA, ASSIGNOR TO WESTINGHOUSE ELECTRIC & MANUFACTURING COMPANY, A CORPORATION OF PENNSYLVANIA.

VACUUM-TUBE FILAMENT.

Application filed April 7, 1922. Serial No. 550,435.

My invention relates to evacuated electric devices of the three-electrode type and particularly to an improved filament-spring design.

5 In its broad aspect, the principal object of my invention is to provide a filament spring of simple, compact and rugged design having highly desirable operating characteristics which admit of material economies in the time 10 necessary for manufacturing tubes embodying the same.

More specifically, another object of my invention is to provide a flexible spring which admits of an extremely large movement incident 15 to the expansion and contraction of the filament and which substantially eliminates all side motion or vibration of the filament.

Another object of my invention is to provide 20 a filament spring which employs a minimum length of material, whereby the potential drop thereacross is decreased. The latter is of importance in view of the relatively low exciting potentials applied to the filament terminals of the tube embodying my invention.

A further object of my invention is to provide 25 a filament spring which tends to minimize vibration of the filament, as caused by a slight jarring of the containing envelope.

In the design and manufacture of a vacuum tube adapted to operate on an extremely low power consumption, as, for instance, a quarter of a watt or less, it was found necessary 30 to redesign every essential element of the usual higher powered tube structure. In general, the several elements must be very closely spaced, hence requiring a filament spring of special design adapted to accomplish the results 35 embodied in the above-mentioned objects and others hereinafter mentioned.

After considerable experimental work, a filament spring was developed which accomplished the desired results. The spring comprises 40 a middle portion and bent-back end portions forming a figure somewhat similar to the letter **S**. A carrier rod and a filament may be secured, respectively, to the free ends of the bent-back portions.

50 Other objects of my invention, as well as details of construction, whereby my invention may be practiced, will be apparent from the following description and claims when read in connection with the accompanying drawing, wherein:

The single figure is a front elevational view of an evacuated electric device embodying my invention, a portion of the containing walls being broken away.

In the single figure of the drawing is shown 60 a vacuum-tube device 1 embodying a design which admits of filament power consumptions of less than one-fourth of a watt, as compared with power consumptions of from three to five watts in the ordinary type of vacuum 65 tube. The vacuum-tube device comprises an enclosing envelope 2 having a re-entrant portion 3 at one end, terminating in a supporting press 4.

A filament spring 5, which may be made 70 of such materials as tungsten or molybdenum, comprises a central portion 6 and upper and lower bent-back portions 7 and 8, respectively. The nature of the bends 9 and 11 is such as to provide a spring action tending 75 to oppose motion of the several bent-back portions thereabout. The upper bent-back portion 7 is somewhat longer than the lower portion 8 and is rigidly secured to a carrier rod 12 in such manner that the several portions of 80 the spring are disposed in a common plane. The carrier 12 may be extended through the press 4 and be provided with a terminal conductor 13 electrically connected thereto.

A filament 14 has one end rigidly secured to 85 the remaining free end of the lower bent-back portion 8 of the filament spring 5 through a nickel-steel connector 14' and the other end rigidly secured to a carrier rod 15 embedded in the press 4 through a nickel-steel connector 90 15'. The nickel-steel connectors 14' and 15' constitute the subject matter of a Patent 1,615,654 of Mark Ryder, Serial No. 599,489, filed November 7, 1922, and patented January 25, 1927, and assigned to the Westinghouse Electric and Manufacturing Company. The carrier rod 15 may be extended through the press and provided with a terminal conductor 16 electrically connected thereto to serve as the remaining supply lead for the 100 filament 14. In the particular type of tube shown, the filament 14 is composed of a platinum strip approximately one-eighth as thick as fine tissue paper and one one-hundredth of an inch wide. The strip is coated with a 105 very thin layer of certain oxides adapted to form a special type of Wehnelt cathode.

A grid member 17 of helical shape is disposed about the filament 14 and is carried by a structure 18 which is supported from the 110

press 4. The structure 18 may be extended through the press 4 by means of a conductor 19 electrically connected thereto to provide an external circuit terminal for the grid.

5 A cylindrical anode or plate member 21 is so disposed as to completely surround the grid and filament elements and is supported by carrier rods 22 and 23 extending from the press 4 and rigidly supported to opposite 10 points on the anode 21. The carrier rod 22 may be extended through the press 4 to provide an external circuit connection by means of a conductor 24 having one end electrically connected thereto.

15 When the filament 14 expands or contracts, it is found that all side motion of the filament 14 is substantially eliminated by reason of the compensating forces introduced in the operation of the spring 5.

20 While I have shown only one embodiment of my invention, for the purpose of describing the same and illustrating the principles thereof, it is capable of various changes and modifications without departing from the 25 spirit of my invention and I desire, therefore, that only such limitations shall be imposed thereon as are indicated in the appended claims or demanded by the prior art.

I claim as my invention:

25 1. In a three-element electron tube comprising a linearly extending filament, a cylindrical grid and a larger cylindrical plate, all concentrically disposed in close relationship, means for supporting the filament comprising, 30 a supporting press, a rod carried by said press and attached to the nearer end of said filament, a second rod carried by said press and extending outside of said cylindrical plate to a point beyond the farther end of the 35 filament, and a spring member comprising a substantially straight central portion and substantially straight bent-back end portions, all of said portions lying in substantially the same plane, one of said bent-back end portions being longer than said central portion, said longer end portion having its free end attached to said second rod, and said half-length end portion having its free end attached to said filament.

ing its free end attached to said second rod, and said half-length end portion having its 50 free end attached to said filament.

2. In an electron tube comprising a linearly extending filament and a substantially concentric cylindrical element disposed in close relationship thereto, means for supporting 55 the filament comprising a supporting press, a rod carried by said press and attached to the nearer end of said filament, a second rod carried by said press and extending outside of said cylindrical element to a point beyond 60 the farther end of the filament, and a spring member comprising a substantially straight central portion and substantially straight bent-back end portions, all of said portions lying in substantially the same plane, one of 65 said bent-back end portions being longer than said central portion, and the other of said bent-back end portions being approximately one-half as long as said central portion, said longer end portion having its free 70 end attached to said second rod, and said half-length end portion having its free end attached to said filament.

3. In a vacuum tube, a group of concentric electrodes including a central linear filament, and means for supporting said filament comprising a standard at one side of said electrodes, and an S-shaped spring extending from said standard beyond the other side of 75 said electrodes and terminating at said filament.

4. In a vacuum tube, a group of concentric electrodes including a central linear filament, and means for supporting said filament, comprising a standard at one side of said electrodes, and an S-shaped spring extending from said standard beyond the other side of 85 said electrodes and terminating at said filament, said spring comprising three substantially straight portions and connecting bends, 90 two of said straight portions being longer than the greatest diameter of the outer electrode.

In testimony whereof, I have hereunto subscribed my name this 21st day of March, 1922.

HARRY M. RYDER.
